ELECTROMAGNETIC RELAY

Alexander J. Lewus, Cicero, Ill.

Application September 24, 1954, Serial No. 458,241

5 Claims. (Cl. 317—176)

The present invention relates to electromagnetic relays and more particularly to such relays of the current responsive or marginal type of the character disclosed in U. S. Patent No. 2,547,131, granted on April 3, 1951 to Alexander J. Lewus, that are especially suited for use in the control circuits of single-phase induction motors of the split-phase or capacitor type.

It is a general object of the present invention to provide an electromagnetic relay of the current-responsive or marginal type that embodies an improved and simplified arrangement for adjusting the magnetic reluctance of the magnetic circuit thereof so as to accommodate ready adjustment of the characteristics of the relay to match the characteristics of a wide range of induction motors of the split-phase or capacitor type.

Another object of the invention is to provide in an electromagnetic relay of the type noted, an improved arrangement for preventing chatter of the armature with respect to the cooperating pole piece when the associated winding is energized with an alternating current.

Further features of the invention pertain to the particular arrangement of the elements of the electromagnetic relay, whereby the above-outlined and additional operating features thereof are attained.

The invention, both as to its organization and method of operation, together with further objects and advantages thereof, will best be understood by reference to the following specification, taken in connection with the accompanying drawing, in which:

Figure 1 is a vertical sectional view of an electromagnetic relay embodying the present invention;

Fig. 2 is an enlarged fragmentary vertical sectional view of the central portion of the relay shown in Fig. 1; and

Fig. 3 is an enlarged plan view of the fragmentary central portion of the relay as shown in Fig. 2.

Referring to the drawing, the electromagnetic relay 10 there illustrated and embodying the features of the present invention comprises a supporting plate 11 formed of insulating material, such, for example, as "Bakelite," and a substantially Z-shaped field element 12 formed of magnetic material and provided with a body 13 terminating in two oppositely directed arms 14 and 15. In the arrangement, the arm 14 extends forwardly with respect to the adjacent lower end of the body 13, and the arm 15 extends rearwardly with respect to the adjacent upper end of the body 13. The arm 14 is suitably secured to the adjacent upper surface of the supporting plate 11 by an arrangement including a plurality of rivet eyelets 16 extending through aligned openings respectively provided in the plate 11 and in the arm 14. Also, a tubular winding spool-carrying member 17 formed of non-magnetic material, such, for example, as brass, is carried by the adjacent upper surface of the arm 14 and secured in place by the eyelets 16 extending through aligned openings provided therein. The member 17 comprises an upstanding substantially cylindrical barrel 18 disposed forwardly with respect to the body 13 of the field

2

element 12 and a lower substantially annular flange 19, the flange 19 being directly secured to the adjacent upper surface of the arm 14, as previously noted. Preferably the barrel 18, as well as the flange 19, of the member 17, has a longitudinally extending slit 20 formed therein in order to interrupt the electrical circuit path there-around so as to minimize eddy currents in the member 17 that are induced therein when the winding provided on the associated winding spool is energized with an alternating current. Also, the relay 10 comprises a unitary winding spool and supported winding that is removably carried by the member 17, the heads of the winding spool being indicated at 21 and 22, and the winding being indicated at 23. The heads 21 and 22 of the winding spool are formed of insulating material, such, for example, as "Bakelite," and the composite winding 23 is formed of suitable conducting wire, such, for example, as copper or the like, individual terminals of the composite winding 23, not shown, being suitably insulated from each other.

Aligned openings 24 and 25 are respectively formed in the plate 11 and in the arm 14, the openings 24 and 25 being arranged in alignment with the inner end of the hollow barrel 18, and the opening 25 being threaded and engaging the threaded exterior surface provided on the inner end of a core element 26 projecting through the openings 24 and 25 and arranged within the barrel 18. The core element 26 is formed of magnetic material and the outer end thereof comprising a pole end projecting toward the outer end of the barrel 18; and arranged in the outer end of the barrel 18 is a first pole piece 27 formed of magnetic material. The first pole piece 27 includes a substantially cup-shaped body 28 arranged within the outer end of the barrel 18 and having an annular groove 28a formed therein that receives a cooperating annular bead 18a formed in the barrel 18 so as to locate the first pole piece 27. More particularly the pre-formed first pole piece 27 may be placed in the outer end of the barrel 18, and the annular bead 18a may be rolled in the barrel 18 into the annular groove 28a so as securely to fasten in place and properly to locate the first pole piece 27. Arranged within the first pole piece 27 is a second pole piece 29 formed of magnetic material and of substantially rod-like form, the exterior surface of the second pole piece 29 being threaded and the inner end thereof being received in a cooperating centrally disposed threaded hole 30 formed in the bottom of the body 28 of the first pole piece 27. The outer end of the second pole piece 29 comprises a pole end and normally terminates adjacent to the outer or pole end of the first pole piece 27, the longitudinal position of the second pole piece 29 being adjustable with respect to the first pole piece 27 by virtue of the cooperation between the threads provided on the exterior surface of the second pole piece 29 and the threaded hole 30 provided in the body 28 of the first pole piece 27. To facilitate longitudinal adjustment of the second pole piece 29 a slot 29a is formed in the outer end thereof that is adapted to receive a screw driver, or the like.

Also, arranged within the hollow first pole piece 27 and in surrounding relation with respect to the second pole piece 29 is a shading coil 31 of substantially washer-like construction; the shading coil 31 being secured in place by a locknut 32 formed either of magnetic or non-magnetic material and carried on the threaded exterior surface of the second pole piece 29.

It will be understood that the pole end of the core element 26 may be adjusted with respect to the adjacent ends of the pole pieces 27 and 29 to accommodate adjustment of a gap provided therebetween by virtue of the arrangement of the engaging threads provided in the opening 25 and upon the outer surface of the inner end of the core element 26. The inner end of the core element 26

has a slot 33 formed therein that is adapted to receive a screw driver, or the like, to facilitate the adjustment noted; and the inner end of the core element 26 also carries a locknut 34 so that the adjusted position thereof within the barrel 18 may be retained by virtue of the co-operation between the locknut 34 and the adjacent lower surface of the plate 11.

In view of the foregoing, it will be understood that a coarse adjustment of the magnetic reluctance of the composite core of the relay 10 may be effected by appropriate adjustment of the longitudinal position of the core element 26 toward and away from the adjacent ends of the pole pieces 27 and 29, and that a fine adjustment of the magnetic reluctance of the composite core of the relay 10 may be effected by appropriate adjustment of the longitudinal position of the second pole element 29 with respect to the first pole element 27. Moreover, it will be understood that the shading coil 31 effects the desired phase-shift between the magnetic fluxes respectively traversing the annular portion of the body 28 of the first pole piece 27 and the second pole piece 29 by virtue of the circumstance that the shading coil 31 surrounds only the second pole piece 29, and, in turn, is surrounded by the annular portion of the body 28 of the first pole piece 27; whereby both the build-up and the decay of the magnetic flux traversing the second pole piece 29 are retarded, while the magnetic flux traversing the annular portion of the body 28 of the first pole piece 27 follows directly the magnetomotive force of the winding 23 when energized with an alternating current.

Further, the relay 10 comprises an armature 35 having a substantially Z-shape and including a body 36 terminating in two oppositely directed arms 37 and 38. The arm 37 projects forwardly with respect to the associated upper end of the body 36 and cooperates with the adjacent outer end of the pole piece 27, while the arm 38 projects rearwardly from the associated lower end of the body 36 and constituting a work lever. The armature 35 is formed of magnetic material and is pivotally mounted upon the upper portion of the body 13 of the field element 12 somewhat above the upper end of the barrel 18 and between the arms 14 and 15 of the field element 12. Specifically, a substantially centrally disposed opening 39 is formed in the upper portion of the field element 12 at the junction between the upper end of the body 13 and the arm 15, whereby two laterally spaced-apart sides 40 extend between the upper end of the body 13 and the rear extremity of the arm 15. Further, two laterally spaced-apart side notches 41 are provided in the sides 40 that respectively receive two laterally spaced-apart tabs, not shown, provided on the opposite sides of the armature 35 adjacent to the junction between the body 36 and the arm 37 thereof. Thus it will be understood that the arrangement, comprising the side notches 41 respectively provided in the lower portions of the sides 40 and merging into the opening 39 and respectively receiving the tabs, not shown, provided on the armature 35, mounts the armature 35 upon the field element 12 for pivotal movements, the arm 37 of the armature 35 being selectively movable toward and away from the pole face of the pole piece 27 about the tabs, not shown, riding in the side notches 41.

The armature 35 is normally biased in its released position illustrated by an arrangement comprising a tension element or spring 42 projecting through the opening 39 and cooperating between the front end of the arm 37 and a screw 43. More particularly, a substantially centrally disposed notch 44 is provided in the front end of the arm 37 that receives the front end of the spring 42, the front end of the spring 42 being arranged in the notch 44 and hooked over the lower surface of the outer end of the arm 37. The rear end of the arm 15 is curved both rearwardly and downwardly and terminates in a tab 45 having an opening therein in which the screw 43 is located, the front end of the screw having a hole therein that re-

ceives the rear end of the spring 42, and the rear end of the screw 43 carrying an associated adjusting nut 46. As described above, the front end of the tension element 42 is pivotally connected to the front end of the arm 37 in the notch 44, while the rear end of the tension element 42 is connected to the screw 43. Thus it will be understood that when the nut 46 is rotated, the screw 43 is moved in the associated opening provided in the tab 45, whereby the position of the front end of the screw 43 is adjusted both in the horizontal and vertical directions effecting corresponding movements of the rear end of the tension element 42. Accordingly, the tension element 42 normally biases the armature 35 in the counterclockwise direction about its pivotal mounting; and the moment of this bias exerted by the tension element 42 upon the front end of the arm 37 may be selectively varied or adjusted depending upon the position of the screw 43 in the associated opening provided in the tab 45. The movement of the bias is adjusted, both by the variation of the tension in the spring 42 and by the variation in the elevation of the front end of the screw 43 with respect to the front end of the arm 37. Further, a hole 37a is provided in the arm 37 and disposed above the slot 29a formed in the outer end of the second pole piece 29 in order to accommodate a screw driver, or the like, so as to facilitate ready adjustment of the second pole piece 29, in the manner previously explained.

Further, the relay 10 comprises a stationary switch spring 47 and a movable switch spring 48, both suitably mounted upon the plate 11 and insulated from each other. The switch springs 47 and 48 are formed of suitable electrical conducting material, and the movable switch spring 48 possesses considerable resiliency. The switch springs 47 and 48 respectively carry stationary and movable contacts 49 and 50 that may be formed of precious metal for the purpose of making and breaking the electrical circuit between the switch springs 47 and 48. Also the movable switch spring 48 carries a pair of laterally spaced-apart upstanding arms 51 carrying a laterally extending pin 52 therebetween upon which an insulating roller 53 is mounted. The roller 53 may be formed of glass, porcelain, or the like, and is readily rotatable upon the pin 52 in order to eliminate friction therebetween. The outer surface of the roller 53 is urged by the resiliency of the movable contact spring 48 into engagement with the adjacent lower surface of the work lever 38 of the armature 35. When the armature 35 occupies its normal released position illustrated, the work lever 38 engaging the outer surface of the roller 53 retains the movable switch spring 48 in its lower position so that the contacts 49 and 50 are disengaged. When the armature 35 is moved into its attracted position with respect to the pole piece 27, it being pivoted in the clockwise direction, as illustrated in Fig. 1, the work lever 38 is effectively moved away from the pin 52 so that the outer surface of the roller 53 rolls upon the work lever 38 due to the resiliency of the movable switch spring 48, whereby the contact 50 is moved into engagement with the contact 49 closing the electric circuit between the switch springs 47 and 48. When the armature 35 is moved into its fully attracted position, the work lever 38 disengages the adjacent surface of the roller 53, so as positively to prevent chatter of the contacts 50 and 49. Subsequently, when the armature 35 is returned to its normal released position, as illustrated in Fig. 1, the work lever 38 engaging the adjacent surface of the roller 53 forces the roller 53, as well as the pin 52 and the movable switch spring 48, downwardly so that the outer surface of the roller 53 rolling upon the adjacent lower surface of the work lever 38 moves the movable switch spring 48 in order again to disengage the movable contact 50 from the stationary contact 49 so as again to interrupt the electric circuit between the switch springs 47 and 48.

In view of the foregoing description of the construc-

tion and arrangement of the relay 10, it will be appreciated that the characteristics thereof may be adjusted over a wide range in order to match the characteristics of a wide range of induction motors of the split-phase or capacitor type. Specifically, the magnetic reluctance of the magnetic circuit of the relay 10 may be readily adjusted by a composite adjustment of the longitudinal position of the core element 26 within the barrel 18 and the longitudinal position of the second pole piece 29 with respect to the first pole piece 27. Moreover, the moment that is exerted by the spring 42 upon the armature 35 may be readily adjusted by appropriate manipulation of the nut 46 upon the screw 43. Among these various adjustments, the alternating current traversing the winding 23 that brings about respective operation and release of the armature 35 may be selectively adjusted.

In view of the foregoing, it is apparent that there has been provided an electromagnetic relay incorporating improved structure for varying the current responses or marginal characteristics thereof over a wide range, thereby lending flexibility to the relay for use in the control circuits of a wide variety of single-phase induction motors of the split-phase or capacitor type.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. An electromagnetic relay comprising a magnetic field element, a longitudinally extending tubular member secured at its inner end to said field element, a longitudinally extending winding carried by said tubular member in surrounding relation therewith and adapted to be energized with an alternating current, a magnetic armature, a pivotal connection between said armature and said field element, said armature having a free end movable toward and away from the outer end of said tubular member, means biasing the free end of said armature away from the outer end of said tubular member, a first longitudinally extending hollow magnetic pole piece secured in the outer end of said tubular member and having an outer end cooperating with the free end of said armature, a second longitudinally extending magnetic pole piece secured within said first pole piece and having an outer end cooperating with the free end of said armature, means for selectively adjusting the longitudinal position of said second pole piece within said first pole piece toward and away from the free end of said armature, a shading coil arranged within said first pole piece and surrounding said second pole piece in order to produce a phase-shift between the magnetic fluxes in said pole pieces when said winding is energized so as to prevent chatter of said armature, said field element having an opening formed therein in longitudinal alignment with said tubular member and communicating with the inner end thereof, a longitudinally extending magnetic core element carried by said field element within said opening and projecting longitudinally into said tubular member and having an outer pole end disposed adjacent to the inner ends of said pole pieces and spaced longitudinally therefrom by a gap positioned within said tubular member and intermediate the ends thereof, and means for selectively adjusting the longitudinal position of said core element in said tubular member so as selectively to adjust the length

of the gap between the pole end of said core element and the adjacent inner ends of said pole pieces.

2. The electromagnetic relay set forth in claim 1, wherein said first pole piece is substantially cup-shaped, said second pole piece is substantially rod-like, and said shading coil is substantially washer-like.

3. The electromagnetic relay set forth in claim 1, wherein said means for selectively adjusting the longitudinal position of said second pole piece within said first pole piece includes cooperating threads respectively provided on the inner end of said second pole piece and in a hole formed in said first pole piece.

4. The electromagnetic relay set forth in claim 1, and further comprising means carried by said second pole piece for securely clamping in place said shading coil.

5. An electromagnetic relay comprising a magnetic field element, a longitudinally extending tubular member secured at its inner end to said field element, a longitudinally extending winding carried by said tubular member in surrounding relation therewith and adapted to be energized with an alternating current, a magnetic armature, a pivotal connection between said armature and said field element, said armature having a free end movable toward and away from the outer end of said tubular member, means biasing the free end of said armature away from the outer end of said tubular member, a first longitudinally extending substantially cup-shaped magnetic pole piece secured in the outer end of said tubular member and having an outer end cooperating with the

free end of said armature, a second longitudinally extending substantially rod-like magnetic pole piece arranged within said first pole piece and having an outer end cooperating with the free end of said armature, the inner end of said second pole piece being threaded and engaging a threaded hole provided in the inner end of said first pole piece to accommodate longitudinal adjustment of the outer end of said second pole piece within said first pole piece toward and away from the free end of said armature, a shading coil arranged within said first pole piece and surrounding said second pole piece in order to produce a phase-shift between the magnetic fluxes in said pole pieces when said winding is energized so as to prevent chatter of said armature, means including a part carried by said second pole piece for securely clamping in place said shading coil, said field element having an opening formed therein in longitudinal alignment with said tubular member and communicating with the inner end thereof, a longitudinally extending magnetic core element carried by said field element within said opening and projecting longitudinally into said tubular member and having an outer pole end disposed adjacent to the inner ends of said pole pieces and spaced longitudinally therefrom by a gap positioned within said tubular member and intermediate the ends thereof, and means for selectively adjusting the longitudinal position of said core element in said tubular member so as selectively to adjust the length of the gap between the pole end of said core element and the adjacent inner ends of said pole pieces.
